(57) **CLAIM**

The ornamental design for a power detector (KW600), as shown and described.

DESCRIPTION

FIG. 1 is a front elevational view of the Power detector (KW600) showing my new design;
 FIG. 2 is a rear elevational view thereof;
 FIG. 3 is a left side view thereof;
 FIG. 4 is a right side view thereof;
 FIG. 5 is an enlarged top plan view thereof;
 FIG. 6 is an enlarged bottom plan view thereof; and,
 FIG. 7 is a perspective view thereof.

The broken lines show portions of the power detector that form no part of the claimed design.
